UNITED STATES PATENT OFFICE.

WALTER D'A. RYAN, OF WEST LYNN, MASSACHUSETTS.

SALUTE-GUN.

No. 809,752.

Specification of Letters Patent.

Patented Jan. 9, 1906.

Application filed April 23, 1904. Serial No. 204,540.

To all whom it may concern:

Be it known that I, WALTER D'A. RYAN, a subject of the King of Great Britain, and a resident of West Lynn, Massachusetts, have 5 invented certain Improvements in Salute-Guns, of which the following is a specification.

My invention consists in certain improvements in the construction of that class of 10 toys designed to successively explode a number of cartridges or charges of fulminate or other explosive, primarily for the purpose of making a loud noise.

The object of the invention is to provide a 15 so-called "gun" of the class noted which shall be of a relatively simple construction and of a nature to permit successive charges to rapidly pass from a magazine to an anvil, so as to be successively exploded by the 20 proper reciprocation of a handle provided with a plunger. This object I attain as hereinafter set forth, reference being had to the accompanying drawings, in which—

Figure 1 is a sectional elevation of my improved salute-gun, showing the same as 25 adapted for application to a cane. Fig. 2 is a sectional plan view on the line 2 2, Fig. 1. Fig. 3 is a sectional plan view on the line 3 3, Fig. 1. Fig. 4 is an elevation of a slightly-modified form of my invention. Fig. 5 is a 30 sectional elevation of a special form of body and valve which may be employed in my invention, and Fig. 6 is an enlarged perspective view of the removable section in which is 35 carried the valve in that form of my invention illustrated in Figs. 4 and 5.

In the above drawings, A is an elongated body, in the construction shown in Fig. 1 of wood, having fastened to its lower end a tubular portion B, preferably of metal, and closed at its lower end. Said lower end is in the present instance provided with a transversely-extending channel, which intersects the main tubular channel of the said end B, 45 there being in the channel and directly in line with the bore of the section B a recess b, wherein the charge or cartridge is exploded. The channel or bore of the end section B is branched toward its upper end, the main 50 portion of it extending in the line of a similar channel within the body portion A of the gun and the other opening into an enlarged portion of the end section B, within which operates a valve C. Said structure C is movable in a line substantially at right angles to the line of the bore b' of the gun, and its end

is provided with an inclined or beveled section c, which projects into said channel, as shown in Fig. 1. This valve is normally retained so as to project into the bore b' by 60 means of a spring c', which enters a recess in the valve and is retained in position by means of a cap c'', placed over the end of a boss b'', formed as part of the section B.

There is through the valve C a passage c'', 65 which under normal conditions is in line with the branch channel b'', though when the valve is moved so as to compress the spring c' said passage c'' is in line with a magazine-tube D, entering the enlarged portion of the 70 section B and extending parallel to the body A of the gun, to which it is fastened in any desired manner. Said magazine-tube has a vertically-extending slit, whereby the number of charges contained in it may be ascertained at a glance, and its upper end is provided with an opening d for the introduction of the charges or cartridges.

The gun is provided with a plunger E, which is movable in the bore or channel of the body 80 portion A, as well as in the continuation of said channel found in the section B, there being upon said plunger a handle e.

The body portion A of the gun and its end section are preferably united, as shown, by 85 providing the said section with a recess in its upper end, into which said body-section fits, and holding the body in position by means of screws, one of which is shown at a.

If now a number of cartridges or charges of 90 some explosive, such as fulminating-powder, be placed through the opening d in the magazine-tube B, the lowermost of these will rest upon the upper face of the valve C, but cannot pass into its passage c'', since this is out of 95 line with the magazine-tube by reason of the action of the spring c' upon said valve. If now the handle e be grasped and the plunger E be forced downward, the end of said plunger will act upon the inclined end of the valve, 100 compressing the spring c' and forcing said valve out of the way, so as to permit the plunger to move downwardly in the bore b'. Such movement of the valve will bring the passage c'' in line with the magazine-tube D 105 and a single cartridge or charge is permitted to enter said passage. Since the passage is not in line with the branch channel b'', said cartridge will be retained in it until the plunger E is raised relatively to the section B, when 110 the spring c' will force the valve into its normal position and the charge or cartridge will

pass from the passage c^3 into the bore b' , finally coming to rest at the bottom of the recess b . If now the plunger E be again moved downwardly, the valve C will be moved into position to receive another charge, while the end of the plunger will forcibly strike the cartridge within said recess b and will explode the same, whatever gases are given off passing out through the transverse passage b^4 in the lower portion of the section B. The upward movement of the plunger E permits a second charge to fall into the recess b , and the above series of operations may be continued as long as cartridges are supplied from the magazine-tube D.

In Figs. 5 and 6 I have illustrated a construction in which the valve for controlling the delivery of charges from the magazine is pivotally supported upon a removable structure inserted in the casting forming the lower section B' of this form of my improved gun. This structure G is preferably cylindrical in form, having in its opposite sides recesses g' and g^2 , placed to be in line with the branch passage b^6 and with the bore b' of the gun. From the lower portion of said structure G extend two arms g^3 , between which the valve C' is carried upon a spindle or pin c^5 , said valve being in the form of a plate having two forwardly-projecting portions c^6 and c^7 , extending in the present case substantially at right angles to it. A spring c^8 , coiled on the pin c^5 , normally retains the valve in the position shown in Fig. 5, with its portion c^6 projecting into the branch passage b^6 and its portion c^7 entering the bore b' . As before, the downward movement of a plunger in the bore b' moves the valve C' to permit a single cartridge c^9 to escape from the magazine which is connected to the passage b^6 into the space between the portions c^6 and c^7 of the valve. When the plunger is again moved upwardly, the spring c^8 turns the valve so that the cartridge is allowed to pass into the bore b' , and so to the recess b in the lower portion of the gun.

If desired, the gun may be constructed, as in Fig. 4, without any body portion A, there being on the upper portion of the magazine D merely a guiding-strap d' , through which is passed the plunger E.

In Fig. 5 the lower section B' is shown as provided with an upwardly-extending lug b^9 for attachment to the body-section A.

It may be noted that one advantage possessed by my improved gun is due to the fact that the body A, being preferably of the length of an ordinary cane, is grasped and held during the operation of the plunger E, so that there is no jarring of the cartridges in the magazine, and consequently no possibility of injury to the cartridges or danger from premature explosion thereof.

I claim as my invention—

1. The combination in a salute-gun of a

structure having a main passage, and a branch passage formed in two parts out of line with each other, a slide-valve having a passage and movable to bring said passage into line with one or other of the parts of the branch passage, and a plunger movable in the main passage for operating the valve and exploding a cartridge, substantially as described.

2. The combination in a salute-gun of a structure provided with two passages opening into a common chamber in different lines, a valve in said chamber having a passage and movable to bring said passage in line with either of said other passages, a spring active on said valve, with a plunger for moving the valve in opposition to said spring, substantially as described.

3. A toy including an elongated tubular body, a plunger therein, a magazine for cartridges, a valve movable by the plunger for successively delivering cartridges from said magazine to the tubular body and a spring independent of the plunger and directly operative upon the valve, said spring tending to move said valve in opposition to the plunger, substantially as described.

4. A toy including a plunger, a structure having an exploding-chamber placed to be entered by the plunger, a magazine, a spring, and a valve actuated thereby independently of said plunger, said valve being movable by the plunger in opposition to said spring and being placed to receive cartridges from the magazine and deliver the same to said exploding-chamber, substantially as described.

5. The combination of a tubular body having its bore provided with a striking-plate, a plunger movable within the bore, a valve mechanically independent of the plunger and of the body, having a portion projecting into said bore so as to be engaged and actuated by the plunger, a spring directly operative upon the valve to move it in opposition to the plunger, and a magazine, said valve being formed to receive a cartridge from the magazine and deliver the same to the bore of the body, and both the plunger and said body being extended so as to permit one of the same being held in position while the other is operated, substantially as described.

6. The combination of a tubular body having within it a branched passage, a magazine, a spring-actuated valve having an opening normally in communication with one branch of said passage, with a plunger in the other branch of the passage and placed to engage the valve to move it in opposition to its spring so that its opening will communicate with the magazine, substantially as described.

7. The combination of a tubular structure having a plunger and a valve having a beveled end projecting into the path of the plunger, a spring tending to retain the valve in such position, and a magazine, said valve hav-

ing an opening which communicates with the magazine when the valve projects into the path of the plunger and with the bore of the tubular structure when said valve is moved 5 back by the plunger, substantially as described.

8. The combination of a tubular body having a magazine attached to its side and provided with a chamber communicating with 10 said magazine and with its bore, a valve in said chamber having through it a passage, a spring normally holding the valve so that its passage connects with the bore of the body, and a plunger in the body for moving the 15 valve so that its passage connects with the magazine, substantially as described.

9. The combination of a tubular body having a transverse opening at its lower end, a plunger movable in the body, a valve carried 20 by the body and movable by the plunger in a straight line substantially at right angles thereto, means in addition to the plunger for positively moving said valve and a magazine connecting with the valve-chamber, there being 25 a passage from the valve-chamber entering the bore of the body between the valve and the transverse opening at the lower end thereof, substantially as described.

10. The combination of a tubular body 30 having a metallic end section, and provided with a chamber connecting with its bore, a plunger movable in the body and in said section, a valve movable in the chamber of the body and provided with an inclined portion, 35 and means for normally holding said portion of the valve in the path of said plunger, said valve having in it an opening normally connecting with the passage from the bore of the body, substantially as described.

40 11. The combination of a tubular body having a magazine, a valve, and a plunger for causing the valve to successively connect with the magazine and the tubular bore of the body, said valve being movable in a line 45 substantially at right angles to the line of the plunger and being placed to be engaged by the end of the same, substantially as described.

12. The combination in a salute-gun of a body having two communicating passages 50 extending adjacent to each other, a magazine

connected to one passage, a plunger in the other passage and a valve having portions normally extending into both passages, said valve being placed to be moved by engagement with the end of the plunger, substantially as described. 55

13. The combination of a tubular body having in it two passages, a plunger in one passage, a magazine connected to the other, and a valve operated by the plunger normally 60 extending into both passages, the portion of said valve which extends into the plunger-passage being inclined to the line of movement of said plunger, and the plunger and magazine being adjacent to each other on the 65 same side of the valve when said plunger is in its raised position, substantially as described.

14. The combination of a tubular body having in it two passages, a plunger in one 70 passage, a magazine connected to the other, and a valve normally extending into both passages, the portion of said valve which extends into the plunger-passage being inclined to the line of movement of said plunger, with 75 a spring tending to retain said inclined portion of the valve projected into the plunger-passage, substantially as described.

15. The combination of a tubular body 80 provided with a striking-plate, a plunger movable within the bore of said body, a valve operated by engagement with the end of the plunger, a spring acting directly on the valve and tending to move it in opposition to the plunger, and a magazine, said valve being 85 formed to receive a cartridge from said magazine and deliver the same to the bore of the tubular body, and said body and the plunger being both of relatively great length so as to permit of one of the same being held while 90 the other is operated, substantially as described.

In testimony whereof I have signed my name to this specification in the presence of two subscribing witnesses.
